Application July 14, 1942, Serial No. 450,899
In Great Britain March 19, 1941

5 Claims. (Cl. 72-66)

This invention relates to the construction of floors and ceilings composed of concrete or like slabs and aims at simplifying the construction of such floors and ceilings.

The invention consists in a method of and means for constructing floors and ceilings, the means provided comprising a set of I-section beams, a set of cradles adapted to stand upon wall portions of a structure and to have interlocking engagement with said beams and to support same in raised positions above said wall portions of a structure, a set of concrete or like slabs having edges shaped to engage into the channels of the beams, and means for holding the beams in parallel and spaced relation, the method of construction consisting in setting up the cradles, beams and slabs, the beams being held in spaced relation by the means provided for this purpose, encasing the cradles and cradle-engaged ends of the beams in a concrete mass which binds to the wall to form an upper portion thereof, feeding concrete mix between each beam and the slabs situated on the respective sides thereof, and removing the spacing means when the concrete has set.

In a preferred form of the invention, there are provided a set of I-section beams each of which has an under-cut longitudinal rib projecting from the outer face of its head and foot, a set of cradles adapted to stand upon wall portions of a structure end to engage said beams by their bottom ribs and support said beams in raised positions above said wall portions of a structure, a set of concrete or like slabs having edges shaped to engage into the channels of the beams, and means for engaging the top ribs of the beams for holding said beams in parallel and spaced relation to one another.

The method of construction according to such preferred form of the invention consists in placing a cradle on the top of a wall, placing another cradle on the top of an opposite wall, engaging the respective ends of a beam with said cradles, erecting another beam in the same manner in parallel and spaced relation to said first beam, locking the beams in such spaced relation by engaging the spacing means with the upper projecting ribs of the beams, sliding a set of slabs along the space between said beams after engaging the edges of the slabs with the respective beams, encasing the cradles and cradle-engaged ends of the beams in a concrete mass which binds to the wall to form an upper portion thereof, feeding concrete mix between each beam and the slabs positioned on the respective sides thereof,

and removing the said spacing means when the concrete has set.

A concrete filling is inserted between the adjacent edges of adjoining blocks and the interposed beam so as to form a solid structure, and if the beams are provided with bottom ribs as well as the top ribs, then these bottom ribs can serve as keys for holding concrete filling inserted into cavities which exist between adjacent blocks at their undersides, thus forming a level continuation of the underfaces of the slabs as required for a ceiling.

The cradles serve the purpose of raising the beams to such an extent as will allow the slabs to be slid into position along the erected beams without obstruction by the tops of the walls.

In order that the invention may be readily understood, reference is directed to the accompanying drawings, wherein:

Figure 1 is a plan view of a partially completed building showing the beams provided by the invention erected and positioned ready for receiving the concrete slabs and showing the positions at which sections through a completed floor and which are shown in other views, are taken.

Figure 2 is a sectional elevation through an assembly provided by the invention and showing steps carried out in constructing the floor.

Figures 3 to 6 inclusive are sections on lines III-III, IV-IV, V-V, and VI-VI respectively on Figure 1, through the completed floor.

Figure 7 is a fragmentary plan view of a beam showing the manner of arranging the spacing means in staggered relation.

Figure 8 is a perspective view showing one end of a beam and one form of cradle for engaging same, and

Figure 9 is a perspective view of another form of cradle.

Referring to the drawings, there is provided a set of I-section beams or girders 10, each of said beams having an undercut longitudinal rib 11 projecting from the outer face of its head flange 12 and a similar rib 13 projecting from the outer face of its foot flange 14.

For the purpose of supporting said beams on partially completed walls there are provided cradles of two different patterns for use in different locations as hereinafter described. The shoe of one pattern shown in Figure 8 comprises a body portion 15 having parallel-walled cavities 16 separated by a cross rib 17, said body portion being provided at its base with projecting flanges 18 constituting feet. The beam to be engaged

with this form of cradle has a notch 19 formed in its bottom rib 13 (Figure 8) and in placing the beam in position same is lowered vertically so that its rib 13 enters the cavities 16, the cross rib 17 of the cradle entering the notch 19; this ensures endwise location of the beam. The cradle of the alternative form (Figure 9) has a body portion 29 in which is formed a longitudinally extending dovetail groove 21 terminating short of one end of said body portion, the latter being provided at its base with projecting flanges 22 constituting feet. A beam is engaged with this form of cradle by sliding said beam endwise into position so that its bottom rib 13 passes along the groove 21. The depth of the cavities 16 in the one form of cradle and of the groove 21 in the other form of cradle is such that the foot flange 14 of the beam is able to seat upon the upper face of the cradle.

Hollow concrete blocks 23 are provided to form the main body of the floor or ceiling. Each of said blocks is shaped at each end to provide a ledge 24 adapted to enter the groove in one side of a beam 10, the disposition of said ledge being such that when same beds on to the foot 14 of the beam, a lower part of the block depends down below the level of said foot 14 of the beam as clearly shown in Figure 2. The sides 25 of said depending part slope outwardly, i. e. diverge from one another in the downward direction. The upper corners of the block are obliquely cut away as at 26 to leave a space between the upper portion of the block and the head flange 12 of the adjacent beam. The upper and the underface of the block are formed with dovetail grooves 27, 28 to serve as concrete mix floated on to the top and underface of the block.

Means is provided for engaging the beams and holding same in spaced relation, during the construction of the floor, said means comprising metal rods 29 (Figure 2) having screw-threaded ends, and pairs of clamping blocks 30 each formed with a recess adapted to engage over one side of an upper rib 11 of a beam 10 and shaped to conform to said rib, the said blocks constituting opposed jaws which are adapted to grip between them the beam rib 11 by tightening up nuts 31 which bear against the outer faces of said blocks 30.

In Figure 1, which serves merely as a key to the other figures of the drawings, the spaces A and B between walls of the building form passages and the space C is one provided for a stairway. Reference D indicates partially completed walls of the building which have been built up all to the same height, and reference E indicates supplementary beams which are bedded into the partially completed walls so as to flush therewith, said supplementary beams providing support for groups F and G of the main beams 10 as hereinafter explained.

Dealing now with the manner of constructing a floor which is to provide also a ceiling for the rooms beneath, cradles 20 of the form shown in Figure 9 are laid upon those walls D of the building which are required to support the ends of the beams 10, said cradles being placed in equidistant spaced-apart relationship. No such support need be provided at points intermediate in the length of a beam 10 where same passes over parting walls. Thus each of the beams which extends right across the building will be supported at its two ends only, by cradles mounted on the partially completed outside walls, one of

these being shown on the extreme left of Figure 1. To effect this mounting of the beams, the cradles 20 are slid on to the ends of the beams 10 so that the grooves 21 of said cradles receive the bottom ribs 13 of the beams. The end walls 32 of the cradles constitute end stops adapted to abut the ends of the beams.

To support those ends of the groups F and G of beams which overlie the suspended supplementary beams E, cradles 15 of the form shown in Figure 8 are laid upon the said supplementary beams E, and the main beams 10 which are to seat upon said cradles, are simply lowered into place so that the bottom rib portions 13 of the beam engage into the cradle cavities 16, the cross-rib 17 of each cradle passing into the notch 19 of the associated beam 10.

The spacing means is then applied to the beams 10 to locate and hold the same in their required spaced-apart positions (Figure 2). This is carried out by bringing the two co-acting blocks 30 provided on one of the rods 29 in position to engage the top rib 11 of one beam 10 and clamping up said blocks by manipulating the nuts 31. Whilst holding the next beam at the correct distance, the blocks 30 provided on the other end of said rod 29 are slid up against the respective sides of the top rib 11 of said second beam and are clamped thereto by tightening up the associated nuts 31. Each rod 29 serves to connect two adjacent beams only, and consecutive rods 29 are disposed in staggered relation as shown in Figure 7.

Having erected the beams 10 as above explained, the spaces between same are filled by sliding a number of blocks 23 along each of such spaces after engaging the ledges 24 of said blocks with the channels of the beams. By reason of the cradles raising the beams well above the partially completed walls D, clearance is provided to allow the depending parts of the blocks to pass over said walls. The blocks are arranged to mutually contact so that they wholly occupy the space between the beams, and their ledges 24 rest on the foot flanges 14 of the beams as is clearly shown in Figure 2.

Blanking tiles 33 which are cut away to fit over the beams 10, are now placed one adjacent to each of the cradles 20 as shown in Figure 4, said tile being positioned so that a face thereof is flush with the inner surface of the wall D. A concrete mass is now built on to the wall D, this mass being retained between an outer brick 34, which is simultaneously laid in position, and the blanking tile 33. Said concrete mass encases and binds on to the cradles and cradle-engaged ends of the beams, thereby securely bonding same. Bricks are now laid in the spaces between the beams 10, to continue the building up of the wall D.

The cradles 15 mounted on the supplementary beams E also are bonded in place by encasing same and the adjacent ends of beams 10 in a concrete mass built on to said beams E, and preferably, before carrying out this operation a reinforcement 35 which may consist of expanded metal fabric, is arranged to upstand behind the end of the adjacent beam 10. The reinforcement plate 35 may be secured to any desired further similar reinforcement 36.

A filling of concrete mix 37 (Figure 2) is now inserted between the beams 10 and the blocks 23 so as to fill the spaces which exist due to the sloped-off faces 26 of the blocks. When this

filling sets it firmly bonds the blocks to the beams. This enables the spacing means comprising the rods 29 and clamping blocks 30 to be removed. Such spacing means is replaced by reinforcement rods 33, the hooked ends of which are engaged over the top ribs 11 of the beams (Figure 3). A concrete mass 39 is now built on to the blocks so as to embed the reinforcement rods 33 and form a floor surface. This concrete mass is extended to provide a body of any desired form about the reinforcements 33 and 36 (Figure 5), for instance, one which forms a handrail-receiving channel 40, and which has a vertical face 41 flush with a face of the associated supplementary beam E. As shown in Figure 4, said concrete mass 39 may be carried over the cradles 20 to unite with the previously laid concrete which bonds and cradles to the wall, the arrangement being such that same provides a surface level with adjoining brickwork to allow the building of the upper part of wall D to progress.

In order to form a ceiling surface a concrete mix 42 is floated on to the underfaces of the blocks 23 (Figure 3). This facing keys into the grooves 28 of the blocks and additionally it is forced into the cavities of dovetail form due to the slope of the side faces 25 of the depending portions of the blocks and this provides a further key for said facing 42. Also the said facing will key on to the bottom ribs 13. This combination will ensure secure bonding of the said facing 42.

In regard to the space H (Figure 1) overlying a wall running parallel to the beams 10, it is preferred to mount an assembly of small blocks which together occupy the full width of the space. That is to say, there will be provided a centre block bedding directly upon the said wall and a pair of side blocks each having one ledge similar to the ledge 24 of the principal blocks adapted to fit in the channel side of the adjacent beam, each of said side blocks having a depending portion which reaches to and beds upon the wall. Thus there is no space between the wall and the blocks requiring to be filled in. Cement filling is run into spaces existing between the centre block and side blocks so as to bond the parts of the assembly.

Referring now to Figures 1 and 6, it will be appreciated that one side of the beam J would be exposed unless some provision were made for encasing same. Accordingly the beam used for this position has a pre-cast mass of concrete 44; that is to say such concrete mass is cast on to the beam over any suitable reinforcing and retaining means 45 such as expanded metal fabric, this operation being carried out in the making of the completed beam before same is taken up for use, the concrete facing 44 being applied, of course, only at those positions where the beam would be otherwise exposed.

It is to be understood that if the structure is not required to provide a floor but only provides a ceiling, then there is no need to apply the upper concrete facing 39.

I claim:

1. In a building construction, the combination with the walls of the building, beam cradles provided with sockets mounted on the tops of said walls, beams of substantially I-shaped cross section each having ribs projecting from the top

and bottom sides thereof, said ribs at the bottoms of the beams having their ends fitting in the sockets of the cradles, pre-formed fireproof slabs having laterally projecting ledges adapted to rest on the lower flanges of the beams and to span the space therebetween, the tops of said slabs lying substantially in the plane of the top flanges of the beams and the bottoms of said slabs lying in a plane below the bottom flanges of the beam, and a settable plastic material covering the top and bottom of said beams and slabs to bond the same together and completely encase the same.

5 2. In a building construction, the combination, with the walls of the building, beam cradles 15 provided with sockets mounted on the tops of said walls, beams of substantially I-shaped cross section each having longitudinally disposed top and bottom ribs, said bottom ribs at the ends of the beams fitting in the sockets of the cradles, 20 preformed fireproof units having ledges projecting from opposite sides thereof and provided at their upper and lower surfaces with a plurality of dove-tailed key channels, said ledges adapted to be supported on the upper sides of the lower 25 flanges of the beams, and the tops of said units being disposed substantially in the plane of the top flanges of the beams while the lower faces thereof are disposed below the lower faces of the bottom flanges of the beam, and a settable plastic 30 material encasing the tops and bottoms of the beams and said units and keying in the channels of said units.

3. In a construction for floors, ceilings and the like, the combination with the walls of the building, 35 of a beam cradle having a cavity positioned on the supporting surface of a building wall, a beam of substantially I-shaped cross section and having a bottom longitudinally disposed rib, the said rib fitting into the cavity of the cradle, pre- 40 cast units disposed between and supported on the lower flanges of the I-beams, and a settable plastic covering and enveloping the beams and said units.

4. In a construction for floors, ceilings, or the like, the combination with the wall of a building, 45 of a beam cradle positioned on the wall and having a socket and a recess separated by an intervening wall, a beam having a longitudinal rib depending from its bottom face, the said rib 50 being provided near its end with a notch to receive said intervening wall of the cradle whereby the portion of said rib nearest the end will fit in said socket and the portion of the rib inwardly of the notch will fit into the said recess of the cradle, a pre-cast unit supported by the beam, and a settable plastic covering for said beam and unit.

5. In a construction for floors, ceilings or the like, the combination with the walls of the building, 60 of a cradle positioned on one of the walls and including a body having a recess opening at one end and closed at the other, a beam including top and bottom flanges and having a rib depending from the bottom flange, the portion of the rib near the end of the beam fitting in said recess when the bottom of the flange rests on top of the cradle, a pre-cast unit supported by a portion of the beam, and a settable plastic covering encasing the unit and beam.

ROBERT HOPEWELL.
